UNITED STATES PATENT OFFICE.

WILLIAM MCCLINTOCK, OF NEW YORK, N. Y.

FIRE-HOSE RACK.

1,109,346.

Specification of Letters Patent.

Patented Sept. 1, 1914.

Application filed October 16, 1911. Serial No. 654,985.

To all whom it may concern:

Be it known that I, WILLIAM MCCLINTOCK, a citizen of the United States of America, and a resident of New York, county and State of New York, have invented certain new and useful Improvements in Fire-Hose Racks, of which the following is a specification, reference being had to the accompanying drawings, forming a part thereof.

My invention relates to improvements in racks for fire hose and its object is to provide an extremely simple structure on which the hose may be folded or looped in such a way as to occupy but little space and be held in such a manner that it may be instantly released and ready for immediate service.

I will describe my invention in the following specification and point out the novel features therein in appended claims.

Referring to the drawings, Figure 1 is a side elevation of a hose rack made according to my invention. Fig. 2 is a plan view of the same. A slightly modified form of the invention is shown in Fig. 3, this figure showing two of its operative positions. In Fig. 4 a detail of construction is shown, this figure being a sectional end elevation on a larger scale of one of the swivel hose supports which form a part of the present invention. Fig. 5 is a plan view of a portion of the rack of Fig. 3 showing its pivoted joints.

Like characters of reference designate corresponding parts in all of the figures.

10 designates a clamp which is adapted to be attached to a pipe 11 through which water is supplied to the hose. This clamp 40 acts as a supporting member for the hose rack and may of course be of any other suitable shape or construction. To the forward end of this clamp-like support is pivotally connected by a vertical bolt or pin 45 12 a frame which comprises two longitudinal parallel arms 13-13 and a connecting back 14. This is a substantially rectangular frame with the front thereof open. The back piece and the parallel arms 13 are 50 preferably made in one piece of metal. The arms may be constructed in the form of channels with the fillers 15 of wood therein which construction is clearly shown in the cross-section in Fig. 6. Near the outer ends 55 of the arms 13 are transverse grooves for supporting trunnions 16 which project from

opposite sides of the hose nozzle. These trunnions are made long enough to reach to the arms so that the inside edges of the arms are parallel even out to their ends so that a free run for the hose is provided for.

20 designates swiveled holding pins which are spaced along each of the arms 13 from the back 14 to the nozzle support and are connected with the arms by vertically disposed screws 21. By this construction all of the holding pins on either one of the arms are free to rotate in substantially one plane.

The preferred construction for the support of the arms 13 is shown in Fig. 3, from which it may be seen that between the vertical pivot 12 and the back piece 14 is a horizontal pivot 17, and a latch 18 arranged to engage a shoulder 19 to hold the arms in a horizontal position. This latch will drop down off the shoulder and allow the arms to drop into an inclined position as shown at 13A in Fig. 3. A set screw 22 may be provided to adjust the degree of this inclination.

One of the advantages of this device is the ease with which the hose may be placed upon it. This is because each of the holding pins is independently rotatable so that they may be moved out of the way of the hose as it is raised up and then out into position to engage the hose loops near the edges of the flattened hose. After the desired number of loops of the hose have been placed upon the rack in the manner shown, the trunnions on the hose nozzle or its coupling are placed in the transverse grooves in the arms 13 provided for them.

Fig. 1 illustrates the manner in which a comparatively large amount of hose is held in the rack so that it occupies but little space. The short holding pins come in actual contact with but a small part of the hose and free air circulation about the folds of the hose is provided for.

To remove the hose when the rack is in a horizontal position, the nozzle is taken off and the hose pulled forward. The loops of hose will be paid off progressively from the rack by the turning of the opposite holding pins about their pivots, and each loop will drop as soon as its pair of holding pins turns. The hose will drop down centrally from the rack and it is not necessary to move each of the hose loops to the front of the arms of the rack before it is released.

But when the preferred form shown in Fig. 3 is used, the first operation which may be performed simultaneously with the removal of the nozzle from the rack, is lifting the 5 rack slightly to release the latch 18. Then the rack will assume an inclined position which will make it easier to pull the hose off the rack as already described, or which if the inclination is sufficient will cause the 10 weight of the hose to rotate all of the holding pins in rapid progression and to be thus released and to drop as soon as the nozzle is removed from the rack. The degree of inclination may be regulated by the screw 22 15 to get the best results with the particular kind of hose used. The object of keeping the outer ends of the arms 13 far enough apart to allow for free passage of the hose is now apparent, for it is important, especially with fire hose, to get instant and unobstructed delivery of the hose when it is required. When the arms are dropped down 20 into a position of inclination sufficient for the weight of the hose to turn the swivels, 25 the nozzle will hold the hose in place until the nozzle is lifted off from the arms. Thus the rack may be used either as a device from which the hose may be easily pulled off by hand or from which it may be delivered automatically. When this preferred form of 30 the invention is used, the rack may be held in its horizontal position until the hose has been placed upon it and the nozzle put in place, after which it may be dropped into 35 its inclined position and left in that position, so that the hose may be immediately delivered upon removal of the nozzle.

What I claim is:

40 1. A hose rack comprising a pair of parallel arms and a plurality of pins, for holding a flattened hose, vertically swiveled in said arms, means for supporting said arms

in a horizontal position and arranged to release the arms when they are slightly elevated and to support them together with 45 said pins in an inclined position, to facilitate the removal of the hose.

2. A hose rack comprising a pair of parallel arms, a connecting back therefor, the outer ends of said arms being provided with 50 means for holding a hose nozzle, and a plurality of swiveled pins, for holding a flattened hose, capable of rotation in substantially one plane spaced along said arms between said back and said nozzle holding 55 means, a pivotal support for said arms, a latch arranged to hold the arms in a horizontal position, and to be released by slightly elevating the arms to allow said arms to drop into an inclined position to 60 facilitate the removal of the hose therefrom.

3. A hose rack comprising a pair of parallel arms, a connecting back therefor, the outer ends of said arms being provided with 65 means for holding a hose nozzle, and a plurality of swiveled pins, for holding a flattened hose, capable of rotation in substantially one plane spaced along said arms between said back and nozzle holding means, a supporting member for the rack, a vertical pivot between said connecting back and the supporting member, a latch arranged to hold the arms in a horizontal position and to be automatically released by slightly 70 elevating the arms to allow said arms to drop into an inclined position to facilitate the removal of the hose therefrom, and means for adjusting the degree of said inclination.

WILLIAM McCLINTOCK.
